AMEL B. BROJUSKA, OF DETROIT, MICHIGAN.

SPARK PLUG.

Application filed January 17, 1925. Serial No. 3,017.

My invention relates to a new and improved spark plug structure for internal combustion engines and an object of my improvements is to provide a spark plug that shall be durable, that shall maintain its insulation, and in which the sparking points are not liable to become fouled.

I secure these objects in the device illustrated in the accompanying drawing in which:—

Figure 1, is a central vertical section of a spark plug embodying my invention.

Figure 2, is a side elevation of the same.

Figure 3, is an inverted plan view.

Figure 4, is a detail showing an insulating washer.

Figure 5, is a detail view in elevation showing the insulating thimble.

Figures 6, 7 and 8, are detail elevational views showing modified constructions.

a , is the porcelain body of approximately the usual construction, except that its lower end does not extend into the cylinder of the engine. a^2 , is a cylindrical axial aperture thru the body a . b is a metal sleeve-like shell formed and screw-threaded at its lower end to engage in the spark plug aperture of the cylinder. The sleeve b is enlarged at its upper end and is hollowed out so that the lower end of the porcelain body a fits therein, resting at its edges against a shoulder a^2 .

c is a second sleeve surrounding the porcelain body a , and provided with a cylindrical screw-threaded portion at its lower end which fits and engages into the cavity at the upper end of the part b . The sleeve c engages against a shoulder a^2 of the porcelain body a and may be made of an insulating material.

The parts b and c are hexagonal at their upper ends so that they may be engaged by a wrench.

The part b is screwed into the spark plug aperture of the cylinder, the part a fitted into the cavity at its upper end, and the sleeve c screwed down until the body a is closely engaged between the parts b and c and held firmly in place gaskets of mica, or asbestos construction, not shown, may be used if desired between part (a), and parts (b), and (c), as is standard practice in the assembly of sparking plugs.

The parts b and c are provided respectively with radial apertures, b^2 , c^2 , to per-

mit the escape of heat from the lower part 55 of the porcelain body a . The lower end of the porcelain body a is provided with a cavity that is the frustum of a cone, its smaller end being upward. The part b is hollowed to prevent a cylindrical chamber coaxial 60 with the cavity of the lower end of the porcelain a . The porcelain or other insulating material a , not dissipating the heat, due to the combustion in the engine cylinder, as rapidly as the metal parts of the plug due 65 to the greater heat conductivity of the metal will therefore have a higher temperature than the metal. The fact of the higher temperature of the insulation has been provided for by the arrangement and design 70 of the plug so that expansion of the plug body, the electrode, or the thimble does not set up or impose strain upon the construction that will cause breakage of the thimble or the plug body. The electrode, positioned 75 on the insulations, when tensioned, only clamps down upon flat surfaces which permit it to expand and contract without damage to the construction even when used under conditions of high temperature. The bushing 80 has been designed to carry heat to the upper part of the plug body and the temperature levels of the insulation have thereby been made to decrease at a more uniform level. This prevents the plug body covered 85 by the bushing from attaining an extremely high temperature under the bushing and a relatively low one a little nearer the top which causes splitting or cracking, for insulation is a relatively poor conductor of 90 heat. The porcelain is formed in this way to obtain the maximum quality of insulating performance from the thimble a . The construction retains the heat at the frustoconical segment of the thimble and the conical recess eliminates crevices which hold carbon formations and permits the perfect theoretical gas turbulence around the spark gap.

d is a thimble of insulating material, preferably compressed mica, bakelite composition, or quartz glass. The thimble d fits into the sleeve b and its upper part is shaped to fit into the cavity of the lower end of the porcelain a . The thimble insulation is a much poorer conductor of heat relatively 100 than the metal of the plug bushing. Metal directly exposed to the cylinder action, due to its greater heat conductivity, remains cool

enough so that oil sprayed against its cooler surface stays to be burnt by the hot gases into carbon. The lower heat conductivity of the thimble and the still lower heat dissipation of the plug insulating body causes the resulting increase in temperature of the frusto-conical thimble portion even above the thimble flange and side wall temperature. This is due to the greater heat conductivity of metal than other material. This construction obviates an expensive or at least an excessively high heat resistant insulating material being used throughout the construction as it is only necessary to have the very best type in the thimble construction. The feature of construction is forming the lower end of the insulating body with the frusto-conical cavity is a means for more adequate and positive insulation due to hot spotting the upper thimble insulating surface and makes possible the rapid drying up or vaporizing of oil, gasoline, carbon, and other matter thrown by the piston on this surface. The thimble's frusto-conical upper form furnishes a large area and the inclined surface presented to the oil, etc., thrown by inertia, or the turbulence of the gas, prevents to a large extent their deposit in the plug and insures their being expelled with the exhaust. The thimble flange also acts as a seal against compression leakage through the plug and its consequent resultant heating of the plug as well as insulating the electrodes if desired or the flange may be cut away to allow passage of the electrodes. The flange edges aid greatly as an insulator. Short-circuiting of the current is practically impossible as the insulator prevents the accumulation of oil, carbon, dirt and other matter that will cling and form on a cooler metal surface and which deposit causes short-circuiting, pre-ignition, missing and to which more than half of the spark plug failures are due. Such chunks of carbon deposit may even cause an open circuit when they get vibrated loose and lodge between the firing points. The insulating flange prevents the oil film forming and so eliminates the ring of carbon on the lower edge of the plug, in this construction and exposes no metal at the edge or plug cavity to the direct action of the combustion chamber, yet provides one of the highest resistant insulations and means for maintaining its efficiency. d^2 is a small aperture formed through the upper end of the thimble d , coaxial with the aperture a^2 . j is a conducting rod, extending coaxially through the aperture a^2 , and provided with screw threads at its upper end that extend beyond the upper end of the porcelain a . j^2 is a circular flange or disc on the rod j , fitting against the under side of the upper end of the thimble d . j^3 is a disc on the lower end of the rod j , and the

upper side of said disc tapers upward into said electrode in the form of a cone. This construction prevents the rapid cooling and also the intense heating of the disc edge. This disc acts as a shield and heat reservoir to keep edge hot between the working stroke cycles, and enables evaporation and drying up of the oil to take place between these cycles. There is considerable space between the rod j and the wall of the aperture a^2 . b^2 , b^3 , are sparking points extending from the edge at the lower end of the thimble d from opposite points toward each other and turning up at their inner ends and extending parallel and adjacent to the rod j .

Said sparking points pass through the flange of the thimble d formed by the turning over of the lower edge of said thimble upon the lower edge of the sleeve b .

The rod j is passed through the aperture d^2 , its flange j^2 engaging the upper end of the thimble d , and the disc j^3 coming just below the inner ends of the sparking points, b^2 and b^3 , its screw-threaded end extending above the porcelain a . The upper surface of the disc j^3 is a tapered incline and carbonization at the arcing points and on the electrode is prevented for the oil runs down the inclined stem. The upturned ends of the electrodes b^2 , b^3 , permits the oil to run from the ends and the sparking gap distance is exactly maintained.

e is a metal cap having its peripheral edge turned downward at e^2 to engage the outer wall at the upper end of the porcelain a . Said metal cap is cut out at its center so as to leave a considerable room between its inner edge and the rod j . f , f , are insulating washers around the rod j , engaging against the upper and lower surfaces of the cap e . g is a metal nut screwed upon the rod j , and engaging above the washer f . k is a conductor wire having the usual terminal k^2 around the rod j and engaging upon the upper surface of the nut g . h is a nut engaging upon the upper end of the rod j and acting the clamp the terminal k^2 against the nut g , so as to connect said terminal with the rod j .

It will be observed that the rod j and connected parts are completely insulated from the porcelain a .

It will also be noticed that the terminals of the sparking points are protected and shielded by the disc, j^3 , so that they are not liable to receive a deposit from the charge.

The porcelain a is not as close to the source of heat as in the usual construction, and apertures, b^4 , c^2 , are provided to permit the escape of heat from the porcelain and maintains a lower and more constant temperature level.

In Figure 6, the rod j is bent over in a part b^{2a} , and terminates in a ball. b^{2a} is a terminal extending vertically downward and

terminating in a ball that is vertically above the ball at the part b^{2a} . In Figure 7, the part j is bent over and terminates in an extended edge and the part b^{3b} extends vertically downward above the terminal of the part b^{2b} . The terminal part b^{3b} has a projection rising at each end of its upper edge so that it presents the appearance of a fork, as shown in the drawing. The part j extends between these projections or in the hollow of the fork and terminates in saw teeth at its lower end.

In Figure 8, the part j is bent sideways in a part b^{2c} , and extends below the vertically downwardly extending part, b^{3c} , and then bends over and terminates at a point near the outer surface of the part, b^{3c} .

In these three modified constructions, the upper terminal is protected by the lower terminal arranged just below it.

In the forms of the device shown in Figures 1 and 8, there are two points at which the spark may pass between the electrodes, thus forming a multiple arc.

I prefer to place a mica washer between the cap e and the upper end of the porcelain a , to position the rod j at its upper end, and to additionally seal possible transmission of heat from cavity α^2 to upper terminal by direct contact of the heated air.

While I have spoken of porcelain in the foregoing specification, of course any insulating material, such as compressed bakelite, would be included.

I have provided apertures, x , x , in the porcelain body to carry away heat from the interior thereof, or the conductor therein.

It will be noted that the same result, that is to say, the multiple arc, is obtained with two electrodes in Figure 8, that is obtained with three in Figure 1.

I prefer to turn the edges of the thimble d over upon the edges of the part b , as shown, to prevent possible short circuiting. This thimble is preferably made slightly shorter than the depth of the cavity in which it fits so that when secured in place by a flange j^2 the turned over portion is forced against the edge of the sleeve b to form a tight joint. This construction permits of a tight joint which heat and expansion will not affect. Bakelite cement or asbestos packing may be used under the flange to make a tighter, more cushioned, and leak-compression proof seat.

What I claim is:—

1. In a spark plug structure a vertical central electrode and an electrode extending inward from said plug and turning vertically upward parallel and adjacent to the first mentioned electrode, the first named electrode terminating in a disc below the upturned end of the electrode extending inward from the plug, said disc having a conical upper surface.

2. A spark plug body, a , the lower end of said body being formed into an annular peripheral fin which tapers from the body downward and forming the wall surrounding a cavity in the lower surface substantially frustro-conical in form. 70

3. In a spark plug structure, an insulating body (a) having an axial aperture therethrough and a cavity in its lower end, a sleeve of conducting material engaging at its upper end around said body and adapted to be connected to an engine cylinder, an insulating washer closing the upper end of said aperture, and an insulating thimble fitting said sleeve and having an end fitting 75 into said cavity and closing the lower end of said aperture, and having its lower edge turned over upon the edge of said sleeve, a conductor passing through said aperture and a disc and nut upon said conductor engaging respectively the outer surface of said thimble and the washer and binding said thimble, washer, and conductor in place, and 80 sparking points passing through the over-turned edge of the thimble. 90

4. In a spark plug structure, a plug of insulating material, a sleeve of conducting material engaging at its upper end around said plug and being adapted to be connected to the engine cylinder, said plug having 95 a frustro-conical wall forming a cavity at its lower end, and a thimble of insulating material fitting into said sleeve and having a frustro-conical end exposed to the combustion chamber fitting into said cavity, which 100 frustro-conical end will form, as explained, a hot-spot in the upper part of said thimble under operating conditions.

5. In a spark plug structure, a plug of insulating material having a cavity at its lower end, a conducting sleeve having its upper part engage around said plug and adapted to be connected to the engine cylinder and having a hollow thimble of insulating material fitting into said sleeve and said 110 sleeve having an end fitting into said cavity and presenting a frustro-conical surface to the combustion chamber.

6. In a spark plug structure, an insulating body formed with a cavity in its lower end, said cavity having frustro-conical walls, a plug bushing, the upper end clamping said insulating body, and an insulating thimble fitting in said bushing and having its edges flanged over to cover the edge 115 of the bushing, and sparking points passing through said flange. 120

7. In a spark plug structure, the combination of an insulating body a , having a cavity at its lower end, a sleeve of conducting 125 material engaging at its upper end around the lower end of said body and extending below said end, and a thimble of thin insulating material fitting against the inner wall of said sleeve and against the wall of 130

4
said cavity at the upper closed end of said thimble, the lower or side wall portion of said thimble being in contact with said sleeve to which it can lose heat rapidly, and 5 the upper part of said thimble in contact with said insulating body to which the thimble will lose heat very slowly and there-

fore have a high temperature for the insulating material has a low rate of heat conductivity, the lower end of said thimble 10 being open to the combustion chamber.

In testimony whereof, I sign this specification.

AMEL B. BROLUSKA.
